UNITED STATES PATENT OFFICE

1,926,946

LAUNDRY APPLIANCE

Henry Hirsch, Jersey City, N. J.

Application April 8, 1933. Serial No. 665,178

9 Claims. (Cl. 40—19.5)

This invention relates to the general art of laundry appliances and has more specific reference to sorting devices uniquely fashioned to receive check or key members of pre-determined 5 formation bearing articles of wearing apparel, or the like.

Those skilled in the art to which this invention appertains are aware that in laundry establishments it is customary to affix indicia-bearing 10 checks or keys to the articles to be cleansed, said checks or keys being normally provided with pins for attaching purposes. In most instances, said keys or checks are contoured to agree with an opening formed in a sorting rack and in view of 15 this arrangement it is obvious that only those garments bearing checks or keys of a particular contour may be inserted in an opening in said rack. In this manner only goods belonging to an individual customer can be segregated on a rack.

20 As will appear hereinafter, my invention performs the functions of a sorting device wherein the holder portion thereof is removably supported at one extremity by a wall-mounted bracket, said bracket being provided with operable means 25 to vary the inclination and declination with relation to the vertical axis of said bracket.

Another important aim of the invention is to provide a novel bracket whereby the holder portion of the device may be affixed thereto during 30 the assembling of the garments thereon, and which permits convenient and facile removal of said holder, together with its supported garments, as desired.

Another object is to provide a novel head portion for the holder, said head including an end or face portion having an opening therethrough, the outline of said opening being individual to the contour of a key element, bearing means to support wearing apparel, or the like.

40 A still further object of the invention resides in the provision of a slidable barrier, borne by said head portion, and normally arranged to be encountered by and moved out of the path of a key element passed through the opening in said head portion, said barrier returning to its normal position after the key element has passed on the holder.

Still another object is to provide spring means, 50 tensioned by the aforesaid movement of said barrier, whereby the latter is positively returned to its normal position to prevent the displacement of key elements from the holder.

Still another object of the invention is to provide means whereby said barrier may be manually operated and restrained in a position out

of the path of key elements to be removed from the holder.

A further object is to provide a novel key element having a head portion adapted to ride along the rails of the holder, said element further having a shank portion, circular in cross-section, and having its surface susceptible of assuming a plurality of shapes, such as annular grooves of varying contours, which register with the outline of an opening formed in the head portion of the device, the particular shape of a key element permitting its insertion into the proper opening without rotation about its vertical axis or similar manipulations.

Other objects and advantages will be apparent 70 as the nature of the invention is better set forth, and it will be understood that changes within the scope of the claims may be resorted to without departing from the spirit of the invention.

In the accompanying drawing:

Figure 1 is a side elevation of my invention, showing one of the keys elements attached thereto, one extremity of the holder portion being broken away to show its attachment to a wall-supported bracket, the latter being shown in section.

Fig. 2 is a front elevation of the device showing the opening in the face portion thereof.

Fig. 3 is a top plan view of the holder removed 80 from the wall-supported bracket.

Fig. 4 is a sectional view taken on the line 4—4 of Fig. 3 and showing the normal position of the barrier prior to the entry of a key element.

Fig. 5 is a view like unto Fig. 4, but showing 90 the key element being passed along the rails of the holder and depicting its co-action with the barrier.

Fig. 6 is a face view of the bracket.

Fig. 7 is a sectional view of the bracket, showing in full lines the inclination of the holder and further illustrating in broken lines the declination of the holder.

Fig. 8 is an elevation of a key element.

Fig. 9 is a transverse sectional view taken on the line 9—9 of Fig. 8.

Referring now more in detail to the drawing, wherein like characters of reference denote similar parts throughout the several views, let 5 indicate the bracket attachable to a wall 6 by means of fastening means 7, said bracket being provided with a front enlargement 8 presenting a socket 9, (see Figs. 1 and 6), having a rear wall 10 and a curved bottom 11, a projection 12 depending from the front portion of the top of said socket 9. 105 It will be noted that said rear wall 10 is provided

with a threaded aperture 13 for the reception of a set-screw 14.

The holder 15 comprises a pair of spaced parallel rails 16 and is provided with a U-bend 17 at 5 one end, (see Fig. 3), while the other extremity carries a head portion 18. In view of the aforesaid arrangement of parts, there is defined a continuous channel between said rails 16 which extends from the face of said head portion 18 to a 10 cross-pin 19 adjacent said U-bend 17.

As the bracket 5 is adapted to support said holder 15, it is obvious that the latter will be inserted in the socket 9 by tilting said holder so that the U-bend 17 rides along the curved bottom 11 15 and rises upwardly until the projection 12 slips within the inner portion of said U-bend 17, the rear wall of said U-bend contacting the head of the set-screw 14 as shown in Fig. 1. It will be obvious that the wedging actions between said U- 20 bend and the projection 12, and between the set-screw and U-bend will maintain the holder in the position indicated. In that the screw 14 may be screwed into and out of the aperture 13, it is manifest that this manipulation may be resorted 25 to to change the angular position of said holder with respect to said bracket. That is, said holder may be given an inclination or a declination with relation to its horizontal axis.

The head portion 18, referred to hereinbefore, 30 embodies side walls 20 and 21 and a face or end portion 22 provided with a recess 23, said side walls presenting aligned, angularly disposed slots 24 and 25, respectively, as shown in Figs. 1 and 4, to receive a movable barrier or bar 26, having 35 headed portions 27 to maintain said barrier in the position indicated. Said side walls are also connected by a pin 28 encircled by a coiled spring 29 having one end 30 braced against the inner surface of said face portion 22, and having its other end portion 31 bearing against said barrier 26, (see Figs. 1 and 2). It will be noted that said portion 31 of said spring 29 is somewhat elongated and is provided with a bend 32 at its extremity. As shown in Fig. 3, plates 33 and 34 40 are attached to the outer surfaces of the ends of said rails 16, fastening means 35 and 36 being employed for this purpose, said fastening means also serving to attach the lower portions of said side walls 20 and 21 to the rails 16 of the holder. 45 The ends of said plates 33 and 34, projecting beyond the edges of each of the rails 16, are in-turned, as indicated at 37 and 38, (see Fig. 2), and spaced apart as shown, to present a gap which combines with said recess 23 in said face portion 22 to define the aforementioned opening for the reception of a key element, the latter being insertable through said opening for subsequent placement in the channel formed between said rails 16. It will be noted that said recess 23, in 50 outline, corresponds to the contour of the head portion 39 of the key element 40 shown in Fig. 8, and also that the edges of said in-turned ends 37 and 38, of plates 33 and 34, are each distinctively fashioned to present projections in the nature of serrations 41, so that the gap or space therebetween coincides with the shape of the shank portion 42 of said key element 40. In view of this arrangement it is obvious that only key elements possessing a contour or shape registering 55 with the contour of said opening can be admitted therethrough.

At this time it is briefly pointed out that said key element 40 is also provided with a circumferential flange 43 at the base of said shank portion 42, and a projection 44 having an aper-

ture 45 for the reception of a ring 46 attached to the heel portion of a pin 47, (see Fig. 1). Said key element 40 is adapted to be passed between the rails 16 of the holder, as pointed out hereinbefore, and in this connection it will be observed 80 the undersurface 39a of said head portion 39 rests on the top edges of the rails 16 and that the distance between said undersurface 39a and the top surface of said circumferential flange 43 is substantially equal to the width of each of said rails 16, thus preventing undue movement of the key elements when placed between said rails. It will be understood that said pin 47, in actual practice, is an oversized safety pin which is caught into the garment or wearing apparel after the 85 goods are received in a laundry establishment and on which, said pin or pins remain until after the goods are assembled into customer groups. The guards of said pins 47 may be provided with a number, as shown, and also the 90 face portion 22 of said head 18 may be supplied with a similar number. For purposes of illustration, the numeral "11" is shown in Figs. 1 and 2.

From the foregoing it will be seen that when a 100 key element 40, supporting any kind of apparel, is presented to the opening defined by the recess 23 and the gap or space between the edges of said in-turned ends 37 and 38, (see Fig. 2), only key elements having a contour coinciding with 105 the outline of said opening can be admitted therein or therethrough.

Assuming now that the proper key element is being presented, said element will pass through the aforesaid opening, the flat undersurface 39a 110 of said head 39, (see Fig. 8), slidably engaging the tops of said rails 16, and as said key element is moved along said rails, said head 39 now engages the barrier 26, which, as shown in Figs. 2 and 4, is normally positioned in the 115 path of said entering key element. In view of the arrangement of angular slots 24 and 25, said barrier 26 is moved upwardly and rearwardly and out of the path of the entering key element, (see Fig. 5), and thus the latter and its burden 120 will then be free to slide along said rails 16 to the cross pin 19, as suggested in Fig. 1. During the aforesaid movement of said barrier 26, the end portion 31 of said spring 29 is also swung upwardly thus tensioning said spring and after 125 the key element has passed beyond said barrier, the tension of said spring returns said barrier to the normal position of the same, as indicated in Fig. 4, and in this position said barrier serves as a stop to prevent the removal of the key elements 130 from the holder 15, until said barrier is manually operated to permit the passage of a key element or elements therewith. In that it is desirable to provide means for maintaining said barrier 26 in an elevated position when key elements are being removed from the holder 15, I 135 propose to provide notches 48 and 49 at the upper ends of said slots 24 and 25, respectively, (see Figs. 1 and 4), and in view of this arrangement, said barrier may be manually moved within said 140 slots 24 and 25 and dropped into notches 48 and 49 so that said barrier will remain in an elevated position above the key elements being removed from the holder 15.

When the barrier 26 is shifted into said notches 145 48 and 49, the end portion 31 of said spring 29 swings upwardly therewith, thus tensioning said spring, whilst the bent portion 32 engages said barrier to assist in its maintenance within said notches. Obviously, said barrier may be ele- 150

vated slightly out of said notches whereupon the former, under tension of spring 29, rides down the slots 24 and 25 to the position indicated in Figs. 2 and 4. Thus the spring 29 causes said barrier to return to its normal position when a key element has been passed along the rails 16, and at the same time said spring holds the barrier in elevated position in said notches 48 and 49.

As pointed out hereinbefore, said holder 15 may be maintained in an inclined or a declined position by the simple expedient of turning the set-screw 14 into or out of the threaded aperture 13. As shown in Fig. 7, (full lines) said set-screw has been retracted and the holder is given a pronounced inclination extending from the U-bend 17 to the head portion 18. Likewise, said holder 15 may be shifted angularly to the declined position indicated by broken lines in Fig. 7, this positioning being effected setting the set-screw up 20 into its threaded aperture. This is a feature of some importance in that a holder inclined as indicated in full lines in Fig. 7 assures that the key elements and attached garments will also have a tendency to ride down the rails 16 toward the cross-pin 19, and that this condition will obtain during the passage of the key elements onto the rails. When key elements and garments are to be removed from the holder before the latter is removed from its bracket, it is sometimes 30 desirable to have said holder assume the declined position shown in broken lines in Fig. 7, in that this declination causes the key elements to ride down the rails and to be conveniently positioned for removal through the head.

It will be understood that after the holder 15 has been loaded with its key elements and garments, the same may be disengaged from the bracket 5 by elevating the head portion 18, while the U-bend 17 slides along the bottom 11 of said socket 9 and is released from engagement with the projection 12. Said holder and its load of garments may then be transferred to another department of the laundry, where single key elements and garments may be removed in the manner set forth hereinbefore.

As pointed out hereinbefore, I have provided a specially designed key element, and since its shank portion is circular in cross-section it may be presented to the opening of the head portion with the assurance that it will enter said opening, provided, of course, the particular contour of said key element corresponds to the contour of said opening. Thus the key element is a universal key since it is not subjected to pre-determined positioning for entry into the opening. The annular grooves formed in the shank portion of the key element may be varied in size, location and general contour. Hence, thousands of combinations may be made up and kept in stock by laundry men and since a particular key element must in contour correspond with the outline of its proper opening in a holder no confusion or mistake can occur. It will be noted in the drawing that the recess 23 and particularly the gap between the inturned ends 37 and 38 are positioned at the extreme front of the holder and hence the opening is first encountered by a key element. My predecessors in this art have favored keys, checks or tags somewhat disk-like or flat and hence such articles, due to their particular shape, must be twisted or otherwise manipulated to pass through an opening. Quite frequently such manipulations permit the insertion of a wrong check or tag.

In view of the particular shape of my key ele-

ment it will enter the proper opening regardless of its position or twisted position in relation to its vertical axis. On inspection of Figs. 2 and 4 it will be noted that the edges of the inturned ends 37 and 38 are relatively thin and hence a flat disk, or the like, presented therebetween might be twisted or sprung to enter the opening and if said disk-like element happened to be the wrong check different customer's apparel would likely be assembled on the same holder. My specially designed universal key element positively precludes such a contingency since it is circular in cross-section and may freely pass through an opening, provided, of course, the opening and key element conform as to shape or contour.

When a holder and its load of garments are bodily removed from the bracket and delivered to another department of a laundry, it is obvious that the individual garments may be subjected to ironing or similar processes, without removing a garment and its key element from the holder. This ideal situation is accomplished due to the fact that each key element is freely rotatable within the rails 16 of the holder and the goods may be turned, re-turned and operated upon individually and collectively without necessitating removal from the holder. Other holders carrying disk-like checks or tags cannot be handled in this way.

In that other supporting means could be substituted for the safety pin shown in the drawing, it is obvious that garments such as men's and women's wearing apparel might be displayed on a holder. Likewise a holder containing such articles could be removed from its bracket and the individual garments examined and re-examined without requiring removal from the holder.

While the present showing is a disclosure of the preferred embodiment of the invention, it is to be understood that the invention is not limited thereto, as various changes in the minor details of construction, proportion and arrangement of parts may be resorted to without departing from the spirit of the invention as defined in the appended claims.

I claim:

1. A device of the character described comprising a wall bracket and a holder comprised of spaced rails, said bracket having a socket to receive one end of said holder and further presenting a projection insertable between said rails adjacent said end of said holder and adjustable means arranged within the socket of said bracket to vary the angular position of said holder.

2. A device of the character described comprising a wall bracket and a holder comprised of spaced rails having a U-bend at one extremity, said bracket having a socket to receive said U-bend and further presenting a projection insertable within said U-bend and a set-screw arranged within the socket of said bracket, said set-screw being adjustable to vary the inclination of said holder.

3. A device of the character described comprising a wall bracket and a holder comprised of spaced rails having a U-bend at one extremity, said bracket having a socket to receive said U-bend and further presenting a projection insertable within said U-bend and cooperating with the walls of said socket whereby said holder is supported by said bracket.

4. A holder having a channel to receive laundry key elements, a head portion for said holder having aligned slots, a barrier shiftably arranged in said slots, said barrier being encoun-

5	tered by a key element to be entered into said channel and being moved thereby out of the path of said element and tension means resisting the movement of said barrier and returning said barrier to its normal position to prevent the escape of a key element from said holder.	in an elevated position to permit the removal of a key element.
10	5. A holder comprising parallel rails spaced apart to present a channel therebetween for receiving laundry key elements, a head portion for said holder, the face portion thereof being provided with an opening, the outline of said opening conforming to the contour on a key element, said head portion being provided with aligned, angularly disposed slots, a barrier shiftably arranged in said slots to be encountered and elevated out of the path of a key element passed through said opening and tension means borne by said head for returning said barrier to its normal position after the passage of a key element to prevent the escape of the latter from the holder.	7. In a device of the character described, the combination of a holder having parallel rails spaced apart to present a channel therebetween, laundry key elements having a shank portion circular in cross-section and presenting annular grooves, and further embodying a head portion adapted to slide on said rails, and a head member carried by said rails having an opening in the face portion thereof, the outline of said opening conforming to the contour on the shank portion of a key element.
15	6. A holder comprising parallel rails spaced apart to present a channel therebetween for receiving laundry key elements, a head portion for said holder, the face portion thereof being provided with an opening, the outline thereof conforming to the contour on a key element, said head portion having its opposite side walls provided with aligned, angularly disposed slots having notches at their upper ends, a barrier mounted in said slots to be encountered and elevated out of the path of a key element passed through said opening and tension means borne by said head for returning said barrier to its normal position after the passage of a key element to prevent the escape of the latter from the holder, said barrier being manually shiftable to fit into the notches of said slots to retain said barrier	8. In a device of the character described, the combination of a holder having parallel rails spaced apart to present a channel therebetween, laundry key elements having a shank portion circular in cross-section and presenting annular grooves, said key elements being freely rotatably borne by said holder and further embodying a head portion adapted to slide on said rails, and a head member carried by said rails having an opening in the face portion thereof, the outline of said opening conforming to the contour on the shank portion of a key element.
20		9. A holder having a channel for receiving laundry key elements, a head carried by one end of said holder, there being an opening in the face of said head, in combination with a key element rotatably borne by said holder, said key element having a head portion adapted to slide on said holder and including a circular shank portion embodying a contour coinciding with the outline of said opening, said key element being insertable through said opening to position the same within said channel.
